JAMES MILNOR HICKS, OF SUMMIT, NEW JERSEY, ASSIGNOR TO AUTO-STOPPER COMPANY,
OF NEW YORK, N. Y.

MEANS FOR SEALING VESSELS.

No. 899,732.

Specification of Letters Patent.

Patented Sept. 29, 1908.

Application filed June 17, 1907. Serial No. 379,502.

To all whom it may concern:

Be it known that I, JAMES MILNOR HICKS, a citizen of the United States, residing at Summit, Union county, New Jersey, have 5 invented certain new and useful Improvements in Means for Sealing Vessels, of which the following is a specification.

My invention relates to means for sealing vessels and it consists in certain elements 10 and combinations of elements fully set out and claimed in the following specification.

In order that those skilled in the art to which my invention appertains, may understand, construct, and use my invention, I 15 will proceed to describe it referring to the accompanying drawings forming part of this specification in which

Figure 1. represents in central section a sealing cap according to one form of my invention above the vessel shown in Fig. 2 to which it is to be applied. Fig. 2. represents in central section the same with the cap secured upon the vessel. Fig. 4. represents in 25 central section another form of my invention and Fig. 5 represents the same applied to a vessel. Fig. 3. is a top view to show that the various forms of my invention are substantially circular. Fig. 6 is still another form and Fig. 7 shows it applied to a vessel.

30 A. in all the figures represents a vessel having a bead on its exterior surrounding the upper part of the neck near its mouth.

B. represents the top surface of a sealing cap.

35 C. Figs. 4 and 5, represents a circumferential flange pendent from the outer diameter of the top surface B. D, Fig. 4, represents a circumferential groove near the base of said flange C, turned inward and contracts the 40 diameter of said flange at this point.

G. represents a sealing wafer inside the cap in all the figures.

45 F, Figs. 2 and 5 and 7 represents a bead upon the exterior of the vessel neck near its mouth.

E, Fig. 1, shows corrugations in a flange pendent from the top surface B, and D, Fig. 1 shows the straight portion of said flange, between the corrugations E.

50 In Fig. 6 E shows the pendent flange curved inward throughout its whole length, contracting the diameter inward.

Fig. 5 shows the cap of Fig. 4 stretched over the bead F upon the vessel neck, with the groove D forced outward to grip the said 55 bead.

Fig. 2 shows the corrugated flange of Fig. 1 stretched over the bead F on the vessel neck.

Fig. 7 shows the cap of Fig. 6 stretched 60 over the bead F on the vessel neck.

It will be seen that in all these various figures the cap is contracted inwardly from its extreme diameter between the top and bottom of the pendent flange previous to being 65 stretched over the bead on the vessel and after being applied the cap flange is bowed outward, to fit the bend.

The principle which is involved in this my invention consists in so contracting the 70 metal of the pendent flange by upsetting the metal previous to the application of the cap to the vessel, that when it is stretched over the bead on the vessel, the contraction will be expanded again to grip the bead on the 75 vessel and thus a greater range of inequality between the flange of the cap and the size of the bead is possible and still give strong grip between the two.

Having now fully described my invention 80 and the manner in which I have embodied it, what I claim as new and as my invention and desire to secure by Letters Patent is

The combination with a vessel having a circumferential enlargement near the top of 85 its neck, of a sealing cap having top surface, a flange pendent from said top surface, said pendent flange being contracted inwardly from its extreme diameter, said inward contraction being of smaller diameter than the 90 said enlargement upon the vessel neck, whereby when said enlargement is entered within said flange, said flange will expand and grip said enlargement and thus secure the said cap firmly upon said vessel, substantially as 95 specified.

In testimony whereof, I have signed my name to this specification in the presence of two subscribing witnesses.

JAMES MILNOR HICKS.
